UNITED STATES PATENT OFFICE.

FREDERICK A. HART, OF JERSEY CITY, NEW JERSEY, ASSIGNEE TO UNDERWOOD COMPUTING MACHINE COMPANY, OF NEW YORK, N. Y., A CORPORATION OF NEW YORK.

COMBINED TYPE-WRITING AND COMPUTING MACHINE.

1,237,513.

Specification of Letters Patent. Patented Aug. 21, 1917.

Application filed July 17, 1911. Serial No. 638,794.

To all whom it may concern:

Be it known that I, FREDERICK A. HART, a citizen of the United States, residing in Jersey City, in the county of Hudson and State 5 of New Jersey, have invented certain new and useful Improvements in Combined Type-Writing and Computing Machines, of which the following is a specification.

This invention relates to computing machines, and is herein illustrated as applied to one of the Underwood-Hanson type illustrated in my pending application No. 466,836, filed December 10, 1908, and in the British Patent No. 3,390 of 1912, in which 15 the keys of the typewriter control the setting of certain pins, and the pins afterward coöperate with the general operator to turn the adding wheels.

One of the principal objects of my invention is to provide simplified and improved 20 means readily applicable to existing machines, for guarding against errors which arise from the liability of the operative to forget to attend to the operation of the 25 general operator after said pins have been set for a number.

My invention is particularly adapted for use in computing machines of the type wherein numbers are recorded in an item 30 register or another temporary recording device and later are carried into a total register or permanent recording device. In such machines the numbers are usually carried into the total register as soon as a line of 35 digits has been completely recorded in the item register. It sometimes happens that the operative forgets to carry the number from the item register to the total register, and thus it sometimes happens that two sets 40 of digits are recorded in the item register and the result will be utterly confused when carried into the total register.

According to the present invention means are provided for automatically notifying the 45 operative when it is time to thus transfer numbers from the item register, and this is preferably done by making it awkward or impossible to operate the numeral keys after the last digit of a number is written,—this 50 digit being usually the one in the units place.

According to the preferred form of the present improvements, a shield or interfering device, or other signal, moves to a position to overlie the numeral keys, whenever

any numeral key has been operated to set 55 the unit pin in any column. This bar interferes with the operation of the keys, or at least warns the operative not to operate the keys and set up new pins before the computing wheels have been operated to register 60 the number that was previously set up on said pins. Said bar is connected to said general operator to be restored thereby to its normal ineffective position back of the numeral keys. When the machine is properly 65 operated, this bar moves automatically into and out of effective position at such times as not to interfere with the operation of the keys, except to prevent the operative from forgetting to attend to the actuation of the 70 general operator.

I preferably provide means normally under tension for moving said bar from normal idle position to effective position; but said means are normally restrained by a 75 latch; and I provide means controlled by the carriage of the typewriter for releasing said latch when the carriage is in position for writing the units digit of a number. Upon operating the general operator, the parts are 80 restored to normal positions.

I also preferably provide a shutter for the dial wheels, which is arranged to cover the writing line on said dial wheels at the same time that the numeral keys are covered by 85 the interceptor bar. This shutter is useful for many purposes, and particularly to prevent the operative from writing the wrong amount in the total column at the right hand side of the work sheet. 90

Other features and advantages will also hereinafter appear.

In the accompanying drawings,

Figure 1 is a sectional side elevation of an Underwood-Hanson combined typewriting and adding machine, showing the present improvements applied thereto; the new parts being in effective positions to guard against the operation of the numeral keys, and to prevent the numbers on the dial 100 wheels from being read. 95

Fig. 2 is a plan view of the jack mechanism, by which the paper carriage selects the denominations of the pins which are set by the keys. 105

Fig. 3 is a perspective rear view of the present improvements in normal ineffective positions.

Fig. 4 is a plan of a set of jacks, with a supernumerary jack made thin and close to the last jack in said set, for reasons which will hereinafter be explained.

Fig. 5 is a perspective view of a button for silencing the interceptor bar and the dial wheel shutter.

Fig. 6 is a part sectional front elevation illustrating the position of the jack-operating dog after it has operated the special jack seen at the bottom of Fig. 4.

Fig. 7 illustrates the special jack as being operated by the dog.

Numeral keys 1 and letter keys 2 depress the usual levers 3 pivoted at the rear of the machine to operate through the usual bell cranks 4, to throw the usual type bars 5 upwardly and rearwardly to strike upon the front side of a platen 6, which is mounted to travel upon a letter-feeding carriage 7, which is driven in the usual manner by a spring 8, and is controlled by letter-feeding devices connecting with a universal bar 9 actuated by heels 10 on the type-bars, and forming part of a frame 11 which has vibrating supports 12 and actuates the usual letter-feeding dogs 12^a, to control escapement wheel 12^b.

Upon said carriage is a tappet or dog 13, which is usually adjustable along the rack bar 14, and has a cam edge to lift, in succession, jacks 15 arranged in a row mounted upon a fulcrum 16. The rear ends 17 of the jacks press down links 18 to vibrate levers 19, which are connected to linkages 20 to lift the rear ends of a series of bars 21, whose forward ends carry racks 22 to mesh with pinions 23 provided upon dial wheels 24, whereby the latter may be rotated.

The numeral keys 1 have stems 25 to operate arms 26 upon linkages 27 to depress any of a set of pins 28 upon the elevated rack bar. As the carriage 7 feeds step-by-step, the rack bars 21 are elevated in succession, and downwardly from each one is projected a pin 28. The rack bars fall to normal positions, thus bringing the depressed pins into the path of a cross bar 29 forming part of a general operator. The general operator, which also comprises a pair of arms 30 and a pair of racks 31 on opposite sides of the machine, is connected by pinions 32 and segments 33 to a shaft 34 which carries the operating handle 35. After the pins are set up by the numeral keys 1, the operative grasps the handle 35 and the general operator is slid forwardly, the bar 29 engaging all of the depressed pins 28 and driving forward the racks 22 corresponding distances, to turn the dial wheels 24 accordingly.

Upon striking a key 1 to print a digit in the units place in the column, and then releasing said key, the carriage 7 advances

one step, and the tappet 13 engages the nose 62 of a special jack 36 placed at the end of the row of jacks and having a link 37 to engage arm 38 upon a rock shaft 39 to rock the latter; said shaft carrying an upstanding arm 40 to which is pivoted the rear end of a latch 41, whereby said latch is withdrawn rearwardly from a tooth or shoulder 42 formed on an arm 43, which extends rearwardly from a rock shaft 44, said arm being then driven up by a spring 45, which is connected to a lever 46 having at one end a fork 47 to engage a pin 48 in said arm 43. This movement of the arm 43 and rock shaft 44 swings forwardly the bar 45 from the dotted line position to the full line position at Fig. 1; said bar being carried upon a pair of uprights 49 rising at the sides of the keyboard from said shaft 44. In the position to which the bar 45 is thus shifted, it overlies the numeral keys 1, and serves to warn the operative not to operate said keys until after the general operator has been operated. The bar interferes with the operation of these keys and therefore silences them, that is, stops the usual operation or activity of the keys.

The movement of the general operator returns the bar 45 to normal and idle position back of the keys. This is effected by a bell crank 50 pivoted upon the machine frame and having an arm 51 to be engaged by a shoulder 52 upon a rack 31 of the general operator. The rack 31, in its forward movement, lifts the arm 51 of said bell crank, and the latter engages an arm 52^a on the lever 46, and vibrates the same, causing the fork 47 thereon to depress the arm 43 and swing back the uprights 49, together with the bar 45. The nose of the latch 41 catches over the shoulder 42 on the arm 43, and thereby holds the bar 45 in idle position; a spring 53 coiled around the rock shaft 39 serving to throw the latch 41 forwardly for this purpose. It will be noted that said latch is slotted between its ends to rest upon a guide pin 54.

At Fig. 2 the jack 36 is of equal size with the other jacks, but at Fig. 4 the nose 62 of the jack 36 is made very thin. The tappet 13 is in such form that the jack 36 will be operated (Fig. 7) and released (Fig. 6) by the time the paper carriage 7 completes its first letter-feeding movement after the printing of a digit in the units place, that is, the letter-feeding movement which occurs as the units type bar returns to normal position. Hence the latch 41, after releasing the bar-throwing arm 43 is caused by the spring 53 to tend to reset said arm 43, so that when the latter is pulled down by the bell-crank 46, the latch snaps into place to hold the bar 45 back in normal position. The arm 52^a of said bell crank normally occupies an elevated position as at Fig. 3, to

permit reciprocation of the general operator 31, etc., at any time, without obstruction from said bell crank.

After reciprocating the handle 35, and thereby throwing the bar 45 back to idle position, the operative may manipulate the keys 1 to set up pins for the next number, and upon the writing of a digit in the next units place the latch 41 will again be withdrawn, and the cycle of operations will be repeated. Thus, by simple means, readily applied to the machine, errors arising from failure to manipulate the handle 35 may be avoided.

15 By turning a button 63, the special jack 36 can be moved to a position to silence or disable the mechanism for shifting the interponent bar. This button is mounted upon the outer end of a stub shaft which is eccentric to the shaft 16 that carries the jacks 15; and on the inner portion of said shaft 64 is a stud 65 which normally is concentric with the shaft 16, and which, by rotation of the button 63 through a half revolution, is 20 lifted above the shaft 16, so that the nose 62 of the special jack 36 is raised too high to be engaged by the tappet 13. It will be seen at Fig. 4, that stud 65 abuts against the end of the shaft 16, which is suitably supported in 25 a bracket or casing 66 independently of said stud 65. To hold the stub shaft 64 where adjusted, a spring 67 presses a ball 68 into a seat 69, Figs. 4 and 5, formed in the stub shaft, said spring being held down by a 30 screw 70, Fig. 5. The stub shaft may have depressions on its opposite sides, and these depressions may be connected by a shallow peripheral groove 71. This disabling of the 35 interponent bar enables the operative to actuate the numeral keys at any desired time.

The interponent bar 45 can be moved to ineffective position by the operative at any time, this being so because it is only held in effective position by the spring 45*. The 45 bar 45 is, therefore, manually movable to ineffective position, and if pushed back far enough is locked in ineffective position by the latch 42. This connection is useful outside the adding zone, because it permits a 50 numeral key to be then actuated by the operative, if desired, without first actuating the general operator. At such times, of course, there is no possibility of setting up numbers on the pins 28, and, therefore, no errors will 55 be made in the computation.

In order to avoid the liability of error, in writing the proper total at the end of each line of writing, I provide a shutter 72 for the dial wheels 24. This shutter is carried 60 upon the ends of arms 73, which are pivoted upon the arbor 74, which carries the dial wheels; and the link 75 is connected to one of said arms 73, and extends rearwardly to an arm 76 pendent from said rock shaft 44, 65 so that when the bar 45 is thrown forwardly

over the keys, the shutter 72 drops behind the sight-opening 77 over the dial wheels, so that the number thereon cannot be read, Fig. 1. This avoids the liability of the operator writing in the total column the 70 amount which shows at the sight hole, after the last number has been written and before the general operator is operated to carry said last number into the adding wheels. The 75 shutter 72 will also be useful for other purposes. It will be understood that the shutter 72 may be thrown out of use by the button 63 in the manner already described.

Variations may be resorted to within the scope of the invention, and portions of the 80 improvements may be used without others.

Having thus described my invention, I claim:

1. In a combined typewriting and computing machine, the combination with a 85 typewriter carriage, type-operating keys, including numeral keys controlling said carriage, computing devices including denominational-determining members associated with said carriage, connections from said 90 numeral keys to control said denominational members and for determining the extent of operation of the computing devices, and an operator for moving the computing devices; of a device normally in idle position, but 95 tending to directly interfere with the operation of said numeral keys, means controlled from said carriage for rendering said device effective to interfere with said numeral keys, and means dependent upon the operation 100 of the general operator for releasing said keys from the effect of said interfering means.

2. In a combined typewriting and computing machine, the combination with a 105 typewriter carriage, type-operating keys, including numeral keys controlling said carriage, computing devices, and connections from said numeral keys to control said computing devices; of a device normally in idle 110 position, but normally tending to interfere directly with the operation of said numeral keys, a latch restraining said device, and means dependent upon the movement of said carriage for releasing said latch. 115

3. In a combined typewriting and computing machine, the combination with a carriage and numeral keys having means to control the same, of computing mechanism including a general operator and also including computing wheels or devices and a row of jacks, one for each wheel, a jack-setting device dependent upon the movement of the carriage, a special jack following the units jack in said row, a shield or device normally occupying a position away from said keys and tending to move to a position overlying said keys, a latch normally restraining said overlying device, and means connected to said special jack for releasing said latch. 120 125 130

4. In a combined typewriting and computing machine, the combination with a carriage and numeral keys having means to control the same, of computing mechanism including a general operator and also including computing wheels or devices and a row of jacks, one for each wheel, a jack-setting device dependent upon the movement of the carriage, a special jack following the units 5 jack in said row, a shield or bar normally occupying a position away from said keys and tending to move to a position overlying said keys, a latch normally restraining said overlying shield, means connected to said special jack for releasing said latch, and means controlled by said general operator for returning said overlying device to normal position.

5. In a combined typewriting and computing machine, the combination with a typewriter carriage, type-operating keys, including numeral keys controlling said carriage, computing devices, connections from said numeral keys for determining the extent of operation of the computing devices, and an operator for moving the computing devices as determined by said numeral keys; of a device normally in idle position, but normally tending to interfere directly with the operation of said numeral keys, a latch restraining said device, means dependent upon the movement of said carriage for releasing said latch, and means controlled by said operator for returning said device to normal position.

6. In a combined typewriting and computing machine, the combination with a typewriter carriage, type-operating keys, including numeral keys controlling said carriage, computing devices including denominational-determining members associated with said carriage, connections from said numeral keys to control said denominational members and for determining the extent of operation of the computing devices, and an operator for moving the computing devices; of a device normally out of effective position, means dependent upon the movement of said carriage to move said device to a position to directly obstruct operation of the numeral keys, said moving means including a part shiftable at will to disable the same, and means dependent upon the operation of the general operator for releasing said keys from said obstructing device.

7. In a combined typewriting and computing machine, the combination with a carriage and numeral keys having means to control the same, of computing mechanism including a general operator and also including computing wheels or devices and a row of jacks, one for each wheel, a jack-setting device dependent upon the movement of the carriage, a special jack following the units jack in said row, a shield or bar nor-

mally occupying a position away from said keys and tending to move to a position overlying said keys, a latch normally restraining said overlying shield, means connected to said special jack for releasing said latch, and means to set said special jack to ineffective position and hold it there. 70

8. The combination with a letter-feeding carriage, numeral keys having means to control the same, and a computing mechanism controlled by said keys, of a general operator for said computing mechanism, a shield or bar to overlie said keys, said shield normally withdrawn from the keys, means dependent upon a movement of said carriage immediately ensuing upon the operation of a key in the units place in a column, for causing said shield to move to a position overlying said keys, means dependent upon the operation of the general operator for restoring said shield to normal position, and means adjustable at will to silence said shield-moving means. 80

9. In a typewriting and computing machine, the combination with a typewriter carriage, type-operating keys including numeral keys, a letter-feeding mechanism for said carriage operable by said keys, computing devices associated with said carriage, means set by said keys for determining the extent of operation of the computing devices and an operator for moving the computing devices, of a pair of arms, a shield or bar carried by said arms and normally adjacent to the numeral keys, a spring tending 90 to swing said arms and bar to cause the latter to cover the numeral keys, a latch restraining said bar, and a latch releaser movable by a part upon said typewriter carriage. 95

10. In a typewriting and computing machine, the combination with a typewriter carriage, type-operating keys including numeral keys, a letter-feeding mechanism for said carriage operable by said keys, computing devices associated with said carriage, means set by said keys for determining the extent of operation of the computing devices, and an operator for moving the computing devices, of a pair of arms, a shield or bar carried by said arms and normally adjacent to the numeral keys, a spring tending 100 to swing said arms and bar to cause the latter to cover the numeral keys, a latch restraining said bar, and a latch releaser movable by a part upon said typewriter carriage. 105

11. The combination with computing keys, a set of computing wheels, and a shutter for said wheels, of means dependent upon the operation of a key to compute a digit in the units place in a column for caus- 110

125

ing said shutter to cover the reading line on said wheels, a key-operation obstructing device made effective by the same means, and means operable from a single point for rendering ineffective both said shutter and said key-obstructing device at will.

12. In a combined typewriting and computing machine, the combination with an item register, and keys for writing and registering numbers in said register, of a total register, means obstructing said keys, a spring normally tending to move said obstructing means to obstructing position, a latch restraining said obstructing means, 15 said latch arranged to be released by the writing of a digit in the units column, and means for carrying a number registered in said item register into said total register, said means arranged to move said obstructing means against the tension of said spring 20 to free said keys and to reset said latch.

13. The combination with a set of numeral keys, of a spring normally tending to interfere with the proper use of said keys, a carriage under the control of said keys, a 25 carriage-controlled latch to restrain said key-blocking means, and means for making said latch control effective or ineffective.

14. The combination with a carriage, of 30 computing wheels forming indicating devices, numeral keys, a shutter called into action by the movement of the carriage at the units position, for preventing the operator from copying off the indicated number, and 35 means for blocking said keys connected to said shutter.

15. The combination of numeral keys, a carriage, a carriage-controlled guard movable to position above the keys, a shutter 40 connected to said guard for obscuring the computed number, and a general operator having means to return the guard and shutter.

16. The combination with numeral keys, 45 denomination devices and a carriage to operate them successively, of a supernumerary denomination device, means connected thereto to interfere with further operation of the keys, and to obscure the computed number, 50 a general operator, and means connected to said general operator to restore the interfering and obscuring means to normal positions.

17. In a computing machine, the combination 55 with numeral keys, a traveling carriage and computing wheels on which said keys are effective in a manner determined by said carriage, of means for visibly warning the operative when not to use said keys, a general operator for actuating said wheels, a 60 bar forming part of said operator, said bar having a notch, and means operated by a side of said notch for making said warning means ineffective.

65 18. In a computing machine, the combina-

tion with numeral keys and a general operator, of a bar adapted to be swung above said keys, and a rock shaft on which it is carried, said general operator having a notched member for controlling said bar.

70

19. The combination with keys and a device for interfering with their operation, of a spring normally tending to make said device effective, a traveling carriage, a dog on said carriage to make said spring effective, 75 computing wheels, a general operator for said computing wheels, and a cam forming part of said operator for making the device ineffective.

20. The combination with computing 80 wheels and numeral keys, of a device for interfering with the operation of said keys, a spring normally tending to make said device effective, a general operator for said wheels, a reciprocating bar forming part of 85 said operator, an arm moved by said operator and means moved by said arm to make said device ineffective.

21. The combination with computing 90 wheels and numeral keys, of a device for interfering with the operation of said keys, a spring normally tending to make said device effective, a general operator for said wheels, a reciprocating bar forming part of 95 said operator, an arm moved by said operator, means moved by said arm to make said device ineffective, and a catch normally holding said device ineffective.

22. The combination with computing 100 wheels and numeral keys, of a device for interfering with the operation of said keys, a spring normally tending to make said device effective, a general operator for said wheels, a reciprocating bar forming part of 105 said operator, an arm moved by said operator, means moved by said arm to make said device ineffective, a catch normally holding said device ineffective, a traveling carriage, and a dog on said carriage for making said catch ineffective.

110

23. The combination with computing 115 wheels and numeral keys, of a device for interfering with the operation of said keys, a spring normally tending to make said device ineffective, a general operator for said wheels, a reciprocating bar forming part of said operator, an arm moved by said operator, means moved by said arm to make said device ineffective, a catch normally holding said device ineffective, a traveling carriage, 120 a dog on said carriage for making said catch ineffective, and means for making said dog ineffective at will.

24. The combination with numeral keys, 125 of a letter-feeding carriage controlled by said keys, a computing mechanism, said carriage movable into and out of a computing zone at each run of the carriage, normally ineffective means for obstructing said numeral keys and adapted to conspicuously 130

and visibly warn the operative that a computation is not complete, a spring normally tending to move said numeral-key-obstructing means to effective position, a latch normally detaining said obstructing means, and means dependent upon the operation of a key in the units place in a column for making said latch ineffective.

25. The combination with numeral keys, 10 of a letter-feeding carriage controlled by said keys, a computing mechanism, said carriage movable into and out of a computing zone at each run of the carriage, normally-ineffective means for obstructing said numeral keys and adapted to conspicuously 15 and visibly warn the operative that a computation is not complete, means dependent upon the operation of a key in the units place in a column for moving said numeral-key-obstructing means to effective position, and means for detaining said obstructing means at its effective position.

26. The combination with a denomination selector, computing keys, a set of computing 25 wheels, a general operator, and a shutter for said wheels, of a traveling carriage, means to coöperate with the carriage at the computation of a digit in the units place in a column, for operating said shutter to cause 30 it to cover the reading line on said wheels,

means made effective by the same means, for interfering with the ordinary use of said keys, and means controlled by the general operator for restoring said shutter-operating means and said interfering means.

35

27. In a combined typewriting and computing machine, the combination with an item register and keys for writing and for registering a number in said item register, 40 of a total register, keys writing but not registering, means including a general operator, for carrying a number registered in said item register into said total register, a shutter for said total register, a silencing device for said writing and registering keys, a single device for causing said silencing device to be effective and said shutter also to overlie said total register during the carrying of the number into said total register, means (including a denomination-selecting 45 member) acting upon the completion of the registering of a number in said item register for causing said single device to act, and means controlled by the general operator for restoring said silencing device and said shutter.
